UNITED STATES PATENT OFFICE

163,950

AUTOMOBILE HOOD ORNAMENT

Samuel R. Jaffe, Chicago, Ill.

Application June 2, 1950, Serial No. 10,306

Term of patent 3½ years

(Cl. D14—18)

To all whom it may concern:

Be it known that I, Samuel R. Jaffe, a citizen of the United States, residing at Chicago, in the county of Cook and State of Illinois, have invented a new, original, and ornamental Design for Automobile Hood Ornament, of which the following is a specification, reference being had to the accompanying drawing, forming a part thereof.

In the drawing:

Fig. 1 is a side elevational view of an automobile hood ornament showing my new design;

Fig. 2 is a plan view thereof;

Fig. 3 is a front elevational view thereof; and

Fig. 4 is a rear elevational view thereof.

I claim:

The ornamental design for an automobile hood ornament, substantially as shown.

SAMUEL R. JAFFE.
